UNITED STATES PATENT OFFICE.

HARRY L. IDE AND HERMAN FERNSTROM, OF SPRINGFIELD, ILLINOIS,
ASSIGNORS TO A. L. IDE & SONS, OF SAME PLACE.

PISTON-VALVE.

SPECIFICATION forming part of Letters Patent No. 618,416, dated January 31, 1899.

Application filed October 10, 1898. Serial No. 693,123. (No model.)

To all whom it may concern:

Be it known that we, HARRY L. IDE and HERMAN FERNSTROM, citizens of the United States, residing at Springfield, in the county 5 of Sangamon and State of Illinois, have invented a certain new and useful Improvement in Piston-Valves, (Case No. 1,) of which the following is a full, clear, concise, and exact description.

10 Our invention relates to piston-valves of the class in which the packing consists of expandable metal rings; and the object of our invention, speaking generally, is to simplify and improve the construction of those parts 15 by which the packing-rings are supported and their adjustment effected and maintained.

A feature of our invention consists in the construction of the follower-head or follower-20 plate, which we have provided with cams and combined with cam-blocks and a clamping device, so that by rotating the follower-plate the cam-blocks are forced against the packing-rings to expand the same, the adjustment 25 thus effected being retained by means of the clamp.

Our invention comprises a piston-body preferably having an extension which may be threaded, a plurality of cam-blocks held 30 in place near the periphery of the piston-body, a follower head or plate carrying cams adapted to engage the cam-blocks, packing-rings interposed between the follower-plate and the piston-body, the said follower-head 35 or follower-plate and piston-body serving to secure the packing-rings in position, and a nut engaging the threaded extension of the piston-body or other suitable clamping device adapted to secure the follower-head in 40 any position to which it may be adjusted and clamp the packing-rings together by means of the follower-head—that is to say, the follower-head is provided with cams and mounted to be rotated to cause the cams thereof to 45 force outwardly the cam-blocks and thus expand and adjust the packing-rings, and thus when the adjustment of the packing-rings has been effected the follower-head, which 50 has been operated to do this work, is clamped in position and the adjustment of the packing-rings is maintained. We preferably use

four cam-blocks, the inner face of each having a central projection or enlargement to come against the edge or face of the cam, the projections or surfaces at the ends of the cam-blocks being just long enough to act as guides and rub against pins placed between the cam-blocks, but not to come in contact with the cam-surface of the follower-head, the center projection or enlargement being the one that 60 rides on the cam-surface.

The construction of our piston-valve is such that the adjustments may be made without removing the same from the steam-chest.

Our invention will be more readily understood by reference to the accompanying drawings, in which—

Figure 1 is an elevation of a piston-valve partially in section, a portion of the steam-chest containing the valve being shown in 70 dotted lines. Fig. 2 is a cross-sectional view of the valve on line 2 2 of Fig. 1. Fig. 3 is a perspective view of two assembled packing-rings. Fig. 4 is a perspective view of the follower-head carrying the cams. Fig. 5 is a 75 perspective view of one of the cam-blocks. Fig. 6 is a longitudinal sectional view of a modified form of a piston-valve embodying our invention.

Like letters indicate like parts throughout 80 the different views.

The preferred embodiment of our invention is illustrated in Figs. 1 and 2. Each end of the piston-body *a* is provided with a threaded portion or extension *b*. A packing-ring *c* is 85 provided with an annular recess *c'* to receive an enlargement of the piston-body. A second packing-ring *d* is provided with an annular recess *d'*, in which the outer periphery of the follower-head *e* is seated. The fol- 90 lower-head is provided with a smooth bore which slips over the extension of the piston-body, said extension thus constituting a centering device or plug. The follower-heads are rotatable in a plane practically perpendicular to the axis of the piston-body. A cam portion (in this instance four cam-blocks *ff*) is placed near the outer periphery of the piston-body and engages the packing-rings. Each cam-block is provided with a central enlargement *f'*, which projects farther toward 95 the center of the piston than the remaining 100

portions of the cam-block, the enlargement riding upon the cam-surface provided upon the follower-head. Distance or guide pins g $g' g'$ are interposed between the cam-blocks 5 to maintain the same in proper position. A pin k is carried by each packing-ring, these pins being interposed between the distance-pins $g' g'$, which are preferably longer than the pins $g g$. By this means the ends of the 10 packing-rings are prevented from coming in alinement. The follower-head carries cams h , corresponding in number to the cam-blocks, each cam in this instance having that surface which is adapted to engage a cam-block eccentric with relation to the center of the piston. 15

In assembling the parts the packing-ring c is first placed in position upon the piston-body, after which the packing-ring d is superimposed upon the packing-ring c , the pins k , 20 carried by the packing-rings, being interposed between the pins $g' g'$. The cam-blocks are then placed between the pins $g g' g'$, &c., the projections f' facing the center of the piston-body. The follower-head is then slipped 25 over the threaded extension. The follower-head may be provided with a series of recesses e' , in which the prongs of a spanner-wrench may be inserted to rotate the follower-head to thrust the cam-blocks outward the desired 30 distance to secure the required expansion of the packing-rings, the outward thrust of the cam-blocks being effected by the engagement of the enlargements f' with the cams upon the follower-head. To maintain the adjustment of the packing-rings, we preferably screw 35 a nut i upon the threaded portion b of the piston-body, said nut engaging the follower-head to secure it in the position to which it has been adjusted and at the same time serving to press the follower-head toward the piston-body to clamp the packing-rings $c d$ firmly 40 in place.

We preferably provide that portion of each extension which projects through the follower-head with means on the end for holding the body of the valve from turning while adjustment is being made at the opposite end, which means preferably consist of a polygonal portion b' , in this instance of hexagonal contour. 45 In effecting, for example, the adjustment of the right-hand end of the piston-valve shown in Fig. 1 the plates l' upon the ends of the steam-chest l may be removed to permit access to both ends of the piston-valve. The 50 left-hand portion b' is engaged by a wrench to prevent the piston-body from turning. The nut i upon the right-hand end is then removed, and the packing-rings expanded by rotating the follower-head with a suitable 55 wrench. After the desired expansion of the packing-rings has been effected the adjustment is secured by screwing the nut i into engagement with the follower-head.

Heretofore it was not practicable to adjust 60 the packing-rings upon the piston-valve without removing the same from the steam-chest, which involved a great deal of trouble and

which made it very difficult to get the exact amount of expansion to the rings to make the valve fit properly. By the structure shown 70 in Figs. 1 and 2 we are enabled to effect and maintain the adjustment without taking the valve from the steam-chest.

In Fig. 6 we have shown a modified form of our improvement in which a threaded 75 sleeve i' is employed, the threaded sleeve engaging a threaded portion b of the piston-body. The follower-head is similar to the follower-head shown in Fig. 4, carrying the cams and serving to clamp the packing-rings 80 in place. The sleeve i' is provided with an annular shoulder, which clamps the follower-head into engagement with the packing-rings. The sleeve acts as a centering-plug for the 85 follower-head.

We do not wish to be limited to the precise form of cam mechanism for expanding the packing-rings employed upon the ends of the piston-body, nor do we wish to be limited to the precise form of that portion of the cam 90 mechanism carried upon each follower-head.

It is obvious that the precise embodiments of our invention herein shown and particularly described may be modified without departing from the spirit of our invention. We 95 do not, therefore, wish to be limited to the precise construction shown; but,

Having thus described our invention, what we claim as new, and desire to secure by these Letters Patent, is—

1. In a piston-valve, the combination with a piston-body, of a follower-head carrying a plurality of cams, said piston-body being provided with a centering device for the follower-head, a ring-packing interposed between the piston-body and the follower-head, a plurality of cam-blocks interposed between the cams and the ring-packing, said follower-head being rotatable in a plane substantially perpendicular to the axis of the piston-body, 105 and suitable means for clamping the ring-packing between the follower-head and the piston-body, substantially as described.

2. In a piston-valve, the combination with a piston-body, of a follower-head carrying a 115 plurality of eccentrically-disposed cams, said piston-body being provided with a centering device for the follower-head, two metallic packing-rings interposed between the piston-body and the follower-head, a plurality of 120 cam-blocks each provided with an extension f' , said follower-head being rotatable in a plane substantially perpendicular to the axis of the piston-body, and means for securing the follower-head in the position to which it 125 is adjusted and serving to press the follower-head in firm engagement with the packing-rings to maintain the packing-rings in place between the piston-body and the follower-head, substantially as described.

3. In a piston-valve, the combination with a piston-body, of a follower-head carrying a plurality of eccentric cams, a centering-plug provided upon the piston-body passing

- through a bore in the follower-head, packing-rings interposed between the follower-head and the piston-body, a plurality of cam-blocks provided with enlargements f' , pins provided
- 5 upon the piston-body serving to separate the cam-blocks, said follower-head being rotatable in a plane substantially perpendicular to the axis of the piston-body, and means for securing the follower-head in the position to
- 10 which it is adjusted and serving to engage the follower-head firmly with the packing-rings to secure the same in position between the follower-head and the piston-body, substantially as described.
- 15 4. In a piston-valve, the combination with a piston-body, of a follower-head carrying a plurality of eccentric cams, a threaded portion carried by the piston-body passing through a bore in the follower-head, a plurality of
- 20 cam-blocks provided with enlargements f' , pins $g\ g'$, $g'\ g''$ provided upon the piston-body serving to separate the cam-blocks, said follower-head being rotatable in a plane substantially perpendicular to the axis of the piston-body, packing-rings interposed between the follower-head and the piston-body, each packing-ring being provided with a pin k interposed between the pins $g'\ g''$, and means for securing the follower-head in the position
- 25 to which it is adjusted and serving to engage the follower-head firmly with the packing-rings to secure the same in position between the follower-head and the piston-body, substantially as described.
- 30 5. In a piston-valve, the combination with a piston-body, of an adjustable follower-head upon each end, each follower-head being provided with a cam-surface, a ring-packing interposed between the piston-body and each
- 35 follower-head, cam-blocks interposed between each cam-surface and ring-packing, and means for clamping the follower-heads in position, whereby the ring-packings between the follower-heads and the piston-body are firmly secured in position and their adjustment maintained, substantially as described.
- 40 6. In a piston-valve, the combination with a piston-body, of an adjustable follower-head upon each end, each follower-head being provided with a cam-surface, a ring-packing interposed between the piston-body and each follower-head, cam-blocks interposed between each cam-surface and ring-packing, means for clamping the follower-heads in position, whereby the ring-packings between the follower-heads and the piston-body are firmly secured in position and their adjustment maintained, substantially as described.
- 45 7. In a piston-valve, the combination with a piston-body, of an adjustable follower-head upon each end, a ring-packing interposed between the piston-body and each follower-head, cam mechanism upon each end of the piston-body for adjusting the ring-packing, a portion of each cam mechanism being carried by a follower-head, and means for clamping the follower-heads in position, whereby the ring-packings between the follower-heads and the piston-body are firmly secured in position and their adjustment maintained, substantially as described.
- 50 8. In witness whereof we heretunto subscribe our names this 7th day of October, A. D. 1898.
